DIVING BOARD

John L. Stark, Cedar Rapids, Iowa

Application April 2, 1940, Serial No. 327,397

5 Claims. (Cl. 272—66)

This invention relates to diving boards and has particular relation to a diving board employing compression or expansion spring means to provide flexibility.

Devices of the character here considered usually employ a laminated board structure which consists of tapered two by fours placed side by side and bolted together. These boards are usually secured to an upright at one end and allowed to rest upon a fulcrum or base which is placed near the center of the board. In this way the board flexes along its entire length.

These structures of the prior art are of necessity subject to a great deal of strain and consequent breakage. The method of construction makes them a highly expensive article of manufacture, and the expense to the owner is excessive inasmuch as these boards must be replaced several times during each season.

The excessive breakage of these boards is caused by the fact that the boards must be so constructed as to achieve a compromise between flexibility and strength. It is obvious that an exceedingly flexible board would lack strength, while a board having the desired strength would lack the necessary flexibility. The inherent nature of this structure makes the combination of these two opposite factors extremely difficult. The usual wooden diving board does not have sufficient strength and, as a result, the boards frequently break at their center sections.

It is a general object of my invention to provide a simple and reliable diving board which achieves both strength and flexibility without requiring a compromise between these two qualities.

Another object of my invention is to provide a diving board which does not require an expensive wooden construction, but rather employs metal to attain strength and flexibility.

It is a further object of my invention to provide a diving board which is simple in construction and requires the minimum of maintenance care.

It is still another object of my invention to provide a diving board which will duplicate the performance of the best wooden board without the attendant breakage of the wooden diving board.

It is another object of my invention to provide a diving board in which the degree of flexibility may be regulated.

It is a still further object of my invention to provide a diving board which is mechanical in nature but which has a minimum of mechanical

structure which would interfere with the use of the diving board.

Other and further features and objects of the invention will be more apparent to those skilled in the art upon a consideration of the accompanying drawings and following specifications, wherein are disclosed several exemplary embodiments of the invention, with the understanding, however, that such changes may be made therein as fall within the scope of the appended claims, without departing from the spirit of the invention.

In said drawings:

Figure 1 is a side view of a diving board constructed according to one embodiment of my invention.

Figure 2 is a top view of the diving board shown in Figure 1.

Figure 3 is a side view of a diving board constructed according to another embodiment of my invention.

Figure 4 is a fragmentary view of the compression spring, used to impart resilience to the diving board shown in Figures 1 and 2, the casing of which has been broken away to show the spring structure in greater detail.

Referring now to the drawings:

Referring now to the drawings and to Figure 1 in particular, the base, indicated generally at 10, supports a board or plank 11 to which a second board 13 is hingedly attached. This plank is supported at the outer end thereof by rods 14, and resilient members, such as compression spring means, indicated generally at 16 which are held by stanchions 17 forming part of the base 10.

The base 10 is constructed according to the usual practice and is preferably made of iron piping. Such a base may include uprights 18, side members 19, and cross or connecting members 19a. Mounted on the base 10 and on the uprights 18 is a rectangular platform 11 preferably made of wood. Hingedly attached thereto is a second platform 13, also preferably of wood.

The hinge 12 is secured to the boards 11 and 13 by bolts 15. Attached to the base at 21 are two stanchions 17 which form an arc with the outer end of the board as a center point. A cross bar 20 is attached to the outer end of the board 13 and has brackets 22 on its outer ends. The brackets 22 are attached to the ends of the rods 14, the other ends of which extend into the forward ends of the casings 23 of the resilient support means 16. A cap 24 having ears 26 thereon is threaded upon the other end of each casing,

and these ears 26 engage corresponding ears on adjustable collars 27 adapted to slide along the lengths of the stanchions 17. A threaded set screw 28 serves to lock each collar 27 in any desired position to adjust the flexibility of the board.

Bracing rods 29 may be utilized to hold the stanchions rigid. One end of a bracing rod may be anchored in one of the stanchion caps 31 and the other end anchored to an upright or crossbar pipe 32 which serves to anchor the inner end of the platform or plank 11.

The rods 14, the resilient members 16, and the bracing rods 29 are substantially parallel and at sufficient distance apart to allow an individual to pass between them.

The boards 11 and 13 and the hinge 12 are preferably covered by a cocoanut mat 33 which extends the entire length of the diving board and is fastened to the under surface of the outer end of the board 13 by a plate 34 which is, in turn, attached to the board by screws 36. The mat is also tacked to the board 13 by tacks 37. The mat is preferably attached to the board 11 only by adjustable shock cords 38 laced through grommets and fastened to the end of the platform. These shock cords maintain tension of the mat over the diving board 11.

The resilient member of compression spring chamber, indicated generally at 16, is shown in greater detail in Figure 4. The rod 14 extends through a lower cover member into the casing 23, and a collar 39 is fastened to the end of the rod by means of a pair of nuts 41. A heavy steel compression spring 42 is inserted between the collar, and the lower end of the casing to provide the "spring" to the diving board. A second light steel spring 43 is placed between collar 39 and the casing cap 24 to take up the back lash and smooth out the rebound of the larger spring 42 and the diving board.

Figure 3 shows another embodiment of my invention. In this embodiment, the stanchions 17 extend downwardly from the cross arms 19 of the base 10 and are held rigid by struts 44 welded in place. The resilient supporting means includes a casing 46 open at one end thereof, and a plunger 47 extending into the open end of the casing. The plunger 47 may be a pipe pivotally attached to the stanchion 17 by collar 27 as already described. A heavy steel compression spring 49 is interposed in the casing 46 between the plunger and the casing cap 48. The casing cap has ears 51 thereon with which the casing is pivotally connected to brackets 22 mounted on the end of the diving board, as previously described in connection with Figures 1 and 2.

Means for taking care of whip or back lash in the board, due to the heavy compression spring, may be provided in the form of a single rod 52 attached to the end of the diving board and to a light tension spring 53. The spring 53 is in turn attached to a cross member between the stanchions 17.

In this embodiment of my invention, since the resilient members are under the board, they may be placed closer together so as to take as little space as possible.

It is obvious that a diving board constructed according to my invention would be equal or superior in flexibility to the customary wooden structure, but would be superior to the wooden board in strength. Metal springs, particularly coil springs, provide flexibility not possible in wood spring boards. In the devices that I have described, it is apparent that strength is not sacrificed in order to secure flexibility.

Although I have described a specific embodiment of my invention, it is apparent that modifications thereof may be made by those skilled in the art. Such modifications may be made without departing from the spirit and scope of my invention as set forth in the appended claims.

I claim as my invention:

1. In a diving board, a fixed platform, a substantially rigid "spring-board" member, means for hingedly connecting the spring board to the platform, stanchion members, and resilient means disposed between the stanchion members and the end of the spring board opposite the hinge means to afford support and spring to the "spring-board."

2. In a diving board, a fixed member, a movable member hingedly attached thereto, a stanchion curved in the arc of a circle having its center at a point near the outer end of the movable member, a resilient member attached at its outer end to the movable member near its outer end, and means for slidably attaching the inner end of the resilient member to the curved stanchion to permit the angle of the resilient member relative to the movable member to be adjusted so as to change the amount of "spring" of the movable member.

3. In a diving board, a platform, a "spring-board" hingedly attached thereto, a frame including a stanchion disposed to substantially form the arc of a circle having its center near the outer end of the "spring-board," a resilient bracing member pivotally connected to the spring board near the outer end thereof and slidably engaged at its inner end with the stanchion, and means for locking the said inner end of the resilient member at any point on the said stanchion.

4. In a diving board, a platform, a substantially rigid spring board hingedly connected thereto, stanchion members mounted at the sides of the platform, resilient means connected to the stanchion members and to the spring board at a point remote from the hinged connection of the board with the platform, the said resilient means including a casing, a compression spring within the casing, and other means for counteracting backlash in the compression spring.

5. In a diving board, a platform frame, a platform supported thereby, stanchions comprising upward extensions of the platform frame, a "springboard" hingedly attached to the platform, and means including coil springs for connecting the stanchions and the springboard at a point remote from the point of attachment of the board to the platform.

JOHN L. STARK.
